UNITED STATES PATENT OFFICE

LEON BENOIT, OF CHICAGO, ILLINOIS

EGG CARTON

Application filed April 14, 1930. Serial No. 443,969.

This invention relates to a carton for the reception of eggs and like commodities. The present improvements are directed more particularly toward a wrapper or enclosure for a cellular filler in which the eggs are placed. An enclosure or wrapper of this kind is advantageous in the respects of simplicity, cheapness, and protection afforded to the filler and its contents. An exemplification 10 of my invention is set forth in the accompanying drawing in the manner following:

Figure 1 is a view in perspective of a wrapper applied around a filler for eggs and the like;

Fig. 2 which is a similar view of the wrapper per se shows the cover slightly raised from closed position;

Fig. 3 is a transverse section through the carton on line 3 of Fig. 1;

Fig. 4 is a detail in section on line 4 of Fig. 3;

Fig. 5 is a fragmentary perspective view of a wrapper having a slightly modified bottom construction; and

Fig. 6 which is a perspective view shows the present improvements embodied in a collapsible carton for containing a filler or the like.

The carton herein illustrated comprises a 30 filler and an enclosure therefor, the latter, as shown in Figs. 1-5, being in the form of a rectangular blank A which may be scored or otherwise treated to provide certain lines of bend a, b, c, d which, together with opposite 35 edges of the blank, define between them a cover 7, back wall 8, bottom 9, a front wall 10 and flap 11 extending laterally from the front wall to underlie the free edge of the cover. A blank answering to this description may be 40 folded upon its bend lines to provide an open ended enclosure for the reception of a filler. It may also be otherwise folded or straightened out into flattened condition so as to occupy a minimum space, as for shipping or 45 storing.

The filler which is adapted to be received within a wrapper of the kind described may comprise a plurality of cross walls B having a plurality of vertical slots extending from 50 one edge for the reception of longitudinally

extending partitions C of which three are shown. Such a filler may, on occasion, be collapsed so as to occupy a minimum space. When opened up for the reception of articles, such as eggs, it provides 55 a plurality of cells or compartments arranged in one or more rows. A filler of this kind is particularly serviceable when placed within a carton, enclosure, or other wrapper by which a covering is provided for the cells, 60 and the contents thereof, both top and bottom. It is with a view to providing such an enclosure which is both economical to produce, secure in its application to the filler, and removable in whole or in part therefrom, 65 that the present invention has been designed.

A wrapper or enclosure of the general kind shown in the drawing is dimensioned so as to closely fit around the filler with which it is associated, and its length is substantially 70 that of the filler measured by the longitudinal partitions thereof. The cover 7 which is hinged to the back wall extends across all the cells of the filler. As shown, it may be transversely weakened along the lines 12 to provide separable sections 14 having capacity 75 for being individually swung upwardly to an open position, as indicated by the dotted lines in Fig. 1. These several cover sections remain integrally joined up to the time that 80 one or more of them is to be severed from the others. The width of each section is substantially that of a single cell of the filler, so that the raising of one such section will expose but a single cell or transverse row of 85 cells. If desired, the cover may be longitudinally weakened along the line 19 close to its hinge (see Figure 1) to facilitate a tearing of each section near the back wall. The user may accordingly remove the contents of the cells so exposed with assurance 90 that the remaining cells will stay covered, as theretofore.

The enclosure or wrapper having these characteristics is further provided with 95 means by which the cover, in its entirety, or the sections thereof individually, are locked in place. As shown such a lock comprises a series of hooks 15 depended from the free edge of the cover, one at the end of each 100

section 14. These hooks, by preference, are each provided with angular faces 16 and 17 meeting at a point 18 which is disposed substantially opposite the inner end of its locking shoulder, and opposite the wider end of the slots wherein the hooks are inserted for locking purposes. It is preferred that the hooks at each end of the wrapper be similarly faced, and oppositely to those of the other end of the enclosure, as shown best in Fig. 2.

The several hooks just described are adapted to co-act with slots 20 which are located, by preference, substantially close to the bend line *d*. These slots are faced upwardly so as to receive the hooks when the cover is brought to a closed position, as shown in Fig. 1. Desirably each slot is enlarged at the end wherein the hook makes final engagement. During the operation of inserting the hooks, it will be found advantageous to flex the wrapper cover from end to end, as shown in Fig. 6, permitting the hooks in the center region of the cover to enter first.

With the cover so flexed the hook shoulders are inclined relatively to the under side of the flap 11 so as to facilitate the final sliding movement incident to the completion of the locking operation. The hooks so secured in place within the tapered slots 20 are normally held against a reverse sliding movement such as would be necessary for their disengagement, by reason of the converging edges of the slits at their narrower ends.

The several improvements which characterize the present carton may be variously combined with other advantageous features, as, for example, depending ridges along opposite edges of the carton bottom, as shown in Fig. 5. These ridges may be formed by extending the front and rear walls 10 slightly below the bottom 9, and by making a reverse bend at *c*, so as to elevate the bottom 9 above the lowermost level of the ridges.

In such a construction the carton, when rested upon a plane surface, supports the filler therewithin at an appreciable height thereabove.

In Fig. 6 I have shown the features of this invention applied to a collapsible carton D which differs from the wrapper already described in no appreciable respect beyond providing end walls 25. The cover construction and its manner of locking is exactly the same as is shown elsewhere in the drawing.

I would have it noted that the wrapper or enclosure in which the present improvements are embodied, provides a serviceable and inexpensive protection for the contents of a carton which are contained in the cells of a filler, and that, in use, so much of the cover as is needed and no more, is opened up to permit access to so much of the carton contents as may be desired; and also that the cover (or its severable components) is pro-

vided with a multiple locking means which may be manipulated in a novel and effective manner to secure the cover in closed position.

I claim:

1. A carton having a hinged cover with locking means in the form of a hook adapted for insertion through a slot formed in a fixed part of the enclosure, the slot being of increased width at the end wherein the hook is disposed when moved to locking position whereby a resistance to reverse movement of the hook is provided. 70
2. A carton for eggs and the like in which is comprised a filler and a collapsible enclosure therefor having a hinged cover provided with transverse lines of severance extending from the forward edge of the cover and terminating at the hinge thereof defining a plurality of separable sections, and a single hook depended from the free edge of each section permitting a severed cover portion to swing to open position independently of the remaining portions of the cover. 80
3. A carton having a hinged cover having weakened lines of severance defining sections separable adjacent the hinge line and also transversely thereof providing independent sections each provided with means for locking same in closed position. 85
4. A carton having a hinged cover with a locking hook adapted for insertion through a slot in a fixed part of the carton whereby to secure the cover down in closed position, the slot being widened near the end toward which the hook is shifted to locking position. 90

In testimony whereof, I have hereunto set my hand this 10th day of April, 1930.

LEON BENOIT.
